No. 657,971.

Patented Sept. 18, 1900.

G. W. VOUGHT.

BOTTLE.

(Application filed Dec. 11, 1899.)

(No Model.)

UNITED STATES PATENT OFFICE.

GEORGE W. VOUGHT, OF NEW YORK, N. Y.

BOTTLE.

SPECIFICATION forming part of Letters Patent No. 657,971, dated September 18, 1900.

Application filed December 11, 1899. Serial No. 739,914. (No model.)

To all whom it may concern:

Be it known that I, GEORGE W. VOUGHT, a citizen of the United States, and a resident of the city of New York, borough of Queens, 5 in the county of Queens and State of New York, have invented a new and Improved Bottle, of which the following is a full, clear, and exact description.

This invention relates to improvements in 10 bottles of the non-refillable class; and the object is to provide a valve mechanism of simple and comparatively-cheap construction that may be applied to bottles of the ordinary shape and by means of which the refilling of 15 a bottle will be effectually prevented.

I will describe a bottle embodying my invention and then point out the novel features in the appended claims.

Reference is to be had to the accompanying 20 drawings, forming a part of this specification, in which similar characters of reference indicate corresponding parts in all the figures.

Figure 1 is a sectional elevation of the neck portion of a bottle, showing a valve mechanism embodying my invention as applied thereto. Fig. 2 is a section on the line 2-2 of Fig. 1. Fig. 3 is a perspective view of a cap employed, and Fig. 4 is a sectional elevation of a modified construction.

30 Referring to the drawings, 1 designates a valve-casing of any suitable material—such, for instance, as glass—arranged within the neck portion 2 of a bottle. On the lower end of the valve-casing 1 is a plate 3, having an 35 opening through it provided with a valve-seat 4 for a valve 5, consisting of cork or other light material. As here shown, the valve is held yieldingly in its seat by means of a band 6 of rubber or the like extended through an 40 opening in the valve and having its ends turned between the lower end of the valve-casing 1 and the plate 3 and held in place by means of cement or plaster 7, which serves to hold the valve-casing and the plate 3 in 45 the bottle. It will be noted that the plate 3 has its edge turned upward to pass into the cement.

The head portion 8 of the valve-casing is 50 provided with a series of circumferential channels or depressions, and in the wall of the head at these depressed portions are perforations 9, through which the liquid may

escape when the bottle is tilted. As a further means for holding the ball-valve 5 yieldingly in its seat I employ a weight 10, which 55 is free to move in the valve-casing and to rest upon the valve 5. The weight 10 is shown in the form of a ball, and it is prevented from moving into the head portion of the valve-casing by means of inwardly-extended lugs 60 11, formed in the casing.

Arranged over the head portion 8 of the valve-casing is a cap 12, having ports 13 through its top wall, and the inner surface of the side wall of this cap is corrugated, as at 65 14, so that liquid may pass along said corrugations to reach the ports 13. By this construction it is obvious that liquid may be easily poured out, as the pressure against the valve 5 will move said valve from its seat, 70 permitting the liquid to pass through the valve-casing and thence through the perforations and ports. It will be practically impossible, however, to refill the bottle by placing it in liquid or otherwise, because the valve 75 5 will engage closely in its seat when pressure is applied by liquid passing into the valve-casing from the outside. The arrangement of the head and the escape-ports for liquid will prevent the insertion of a wire or 80 similar instrument to move the valve from its seat.

The cap is held rigidly in place by means of lugs 15 on its lower end, having inwardly-turned portions 16 to engage against the under side of an annular flange 17, formed on the valve-casing. At opposite sides this flange 17 is provided with openings through which the lugs 15 may pass when the cap is placed in position. This cap is to be placed in position while the cement 7 is still in a soft or yielding condition, so that after passing the lugs through the opposite openings of the flange the cap may be given a slight rotary movement to bring the portion 16 underneath 90 the flange, and of course when the cement hardens the cap cannot be again turned to a position to remove it.

A vent for the inlet of air may be provided while inserting the valve mechanism by first 100 placing a string *x* in the neck of the bottle, and then before the cement hardens the string may be pulled out, leaving a very fine opening, or the string may be doubled substan-

tially in the form of a chain, and then by pulling it to cause the links to come closer together a vent will be formed and the string may remain in the bottle-neck.

5 Instead of the spring-yielding cord or rubber 6 for holding the valve 5 in position I may employ a metal spring 18, as indicated in Fig. 4, this spring 18 being connected at one end to the ball and at the other end to a bridge-
10 piece 19, connected to the plate 3.

Having thus described my invention, I claim as new and desire to secure by Letters Patent—

1. In a bottle, a valve-casing arranged in
15 the neck portion thereof, a valve held yield-
ingly in a seat formed in the lower portion of
the casing, a head on said casing having an-
nular channels and perforations through the
wall of the head in said channels, and a cap
20 for fitting over the head of the valve-casing,
the said cap having a port through its top
wall and having channels in the inner side of
its side wall, substantially as specified.

2. In a bottle, a valve-casing having a head portion provided with perforations and an-
nular channels, a plate in the lower end of
said casing and having a valve-controlled
opening, a cap fitted over the head portion of
the valve-casing and having ports and chan-
nels in the inner side of its side wall, and lugs
30 extended from said cap and having hooked
portions for engaging underneath a flange
formed on the casing, substantially as speci-
fied.

3. In a bottle, a valve-casing arranged in 35
the neck portion of the bottle, a cement for
securing the casing, and a string or the like
extended through the cement and adapted
when drawn to form a vent.

In testimony whereof I have signed my 40
name to this specification in the presence of
two subscribing witnesses.

GEORGE W. VOUGHT.
